GRAIN SEPARATOR

Haakon Mjolsness, deceased, late of Minneapolis, Minn., by Olga A. Mjolsness, administratrix, Minneapolis, Minn., assignor to Haaky Manufacturing Company, St. Paul, Minn., a corporation of Minnesota

Original application July 17, 1936, Serial No. 91,146. Divided and this application August 12, 1940, Serial No. 352,244

2 Claims. (Cl. 209—12)

This invention relates to an improvement in grain separator wherein it is desired to provide a separating device in which certain of the materials found in grain are separated from the grains and in which the grain is separated from foreign material.

This application is a division of the deceased inventor's application Serial No. 91,146, filed July 17, 1936, for improvement in "Grain separator and aspirator," now Patent 2,211,575 granted August 13, 1940.

It is an object of this invention to provide a grain separating device embodying a substantially cylindrical housing having an axis which is usually vertical. A cylindrical screen is rotatable within this cylindrical body and this screen separates grain such as wheat, seeds and the like, from longer grain, such as oats. Between the concentric casing and screen, there is provided a series of inclined means which bear against the relatively rotatable cylindrical screen and which guide larger particles of foreign material upwardly to separate these particles from the materials such as oats, and the like, which may pass by the inclined guide means.

It is a feature of this invention that the inclined screen engaging means which may be in the form of inclined or diagonally extending wire brushes or the like, act to comb from the surface of the screen larger particles of foreign material incapable of passing through the screen and in the rotation of the screen act to guide these large particles up the incline which will eventually separate these larger particles from other material incapable of passing through the screen. Thus the separator acts as a scalper to scalp straw, sticks and other larger material from the larger grain and to separate these materials from the grain incapable of passing through the cylindrical screen.

An important feature of the separator resides in the provision of wire brushes which contact the screen surface adjustably and which are positioned diagonally or spirally. These brushes are provided with wire bristles and the brush is so shaped as to provide an arcuated bristle engaging surface against the cylindrical rotatable screen. These brushes act to retard the foreign material and cause the same to ride up over the brushes or up the incline of the brushes to the top surface of the same. Material such as sticks, stones, corn and other foreign material will ride up the incline of the first brush and drop down upon the second brush. The rotation of the screen will eventually carry this material up over the second

brush to drop onto the third brush, and so on until the material has passed over the entire series of brushes. Thus the grain is thoroughly cleaned of any foreign material and the desired particles of grain, such as wheat and the like, are permitted to pass through the vertical rotating screen. After the ends of the bristles of the inclined brushes wear due to their contact with the perforated screen surface, these brushes may be readily adjusted into proper position so as to again contact the surface of the perforated screen.

These and other objects and novel features of the invention will be more clearly and fully set forth in the following specification and claims.

In the drawings forming a part of this specification:

Figure 1 is a vertical section through the separator, illustrating the relationship of the various parts.

Figure 2 is a cross-sectional view transversely through the separator, the position of the section being indicated by the line 2—2 of Figure 1.

Figure 3 is a diagrammatic perspective view in section, illustrating the manner in which the inclined brushes are mounted with respect to the screen.

The separator A includes a hollow cylindrical casing indicated in general by the numeral 10. This casing 10 includes a transmission chamber 11 defined by transversely or horizontally extending partition walls or floors 12 and 13. The transmission casing 14 rests upon the partition 13 and is supported by a central supporting plug 15 which extends below the partition 13 and is secured to the side walls of the casing 10 by means of radially extending braces 16. The outer ends of the braces 16 are somewhat above the connection with the plug 15 so that by tightening the braces 16 the plug 15 may be elevated. The transmission casing 14 includes a removable covering 17 supported to the casing by means of suitable supporting bolts or other means. A bearing 19 is provided in the casing 14 and a suitable bearing 20 is provided in the cover 17 to support the stub shaft 21. A worm wheel or gear 22 is secured to rotate with the shaft 21 and is operated by a suitable worm 23 on the drive shaft 24. A drive pulley 25 is provided on the shaft 24 by means of which the shaft 24 and consequently the gears 22 and 23 and the stub shaft 21 may be operated.

A spider 26 is rotatably secured to the stub shaft 21 for rotation therewith and projects beyond the stub shaft to form a socket for receiv-

ing the lower end of the concentric vertical shaft 27. Thus the hub 29 of the spider 26 acts to connect or to form a spline connection between the shaft 21 and the shaft 27. Paddle means 30 are provided on the spider 26 to rotate seeds resting upon the floor or partition 12 toward a suitable outlet not illustrated in the drawings. The upper surface of the spider 26 is provided with bearing surfaces 31 upon which a floating disc-shaped screen 32 is designed to rest. The screen 32 is held from rotation by any suitable means, not illustrated in the drawings, which ordinarily constitute a pin on the peripheral edge of the screen which extends through a vertical slot in the casing 10. Above the screen 32, the inventor provides a spider 33 which rotates over the surface of the screen and tends to force any wheat or other grain resting upon the surface of the screen 32 toward a suitable outlet not illustrated in Figure 1 of the drawings.

A cone 34 is mounted on the shaft 27 and is connected with a ring 35 by means of spaced connecting ears 36. The ears 36 extend down into the spider 33 and obtain support therefrom, the cone 34, the ring 35, and the connecting ears 36 all rotating in unison with the spider 33 and the shaft 27. The cylindrical screen 37 is supported upon the ring 35 and projects upwardly therefrom. The upper extremity of the screen 37 is reinforced by a suitable reinforcing ring 39.

A ring shaped partition 40 is provided within a bead 41 in the casing 10, this partition encircling the screen 37. A suitable gasket 42 is provided on the ring 40 which seals the joint between the ring 40 and the lower portion of the cylindrical screen 37. This gasket prevents grain and the like from passing between the screen and the ring 40 and dropping into the lower portion of the separator.

An inclined wall 43 is provided on one side of the ring 40 beneath the hopper 44. The hopper 44 extends through the wall of the casing 10 and is provided with a gate closure 45 which is vertically reciprocable in tracks 46. The gate closure 45 is provided with a rack 47 which is engaged by a pinion 48 on a shaft 50. A hand wheel not illustrated in the drawings, externally of the casing 10, may be rotated to rotate the shaft 50 and pinion 48 to raise and lower the gate 45 in the track 46. The feed of unseparated grain into the casing is regulated by this means. A series of inclined brushes 51 are positioned between the casing wall 10 and the screen 37. One end of each of these brushes extends into contact with the partition wall or shelf 40, while the other end of each brush is spaced considerably above this shelf. The arrangement of the brushes is best illustrated in Figures 2 and 3 of the drawings.

Each brush 51 comprises bristles 52 set into a backing of wood or the like 53. A metal covering plate 54 is positioned on top of each of the brushes 53 and this plate 54 extends partially over the bristles to assist in supporting the same. Each brush is supported on an inclined shelf or bracket 55 which is rigidly secured to the casing wall. The brushes 51 are adjustable toward and away from the screen 37 by means of adjusting screws 56 which extend into the backing 53 of the brushes and which extend through the casing walls 10.

Interposed between the screen 37 and the cone 34, the inventor provides a cone 57 which extends at its lower extremity into close relationship with the bottom of the ring 35. The cone 57 is integrally secured to a sleeve 59 which is secured

in telescoping relation with a sleeve 60 extending coaxial with the screen 37. A supporting spider 61 supports the sleeve 59 rotatable upon the shaft 27, the shaft 27 rotating within the bearing 62 of the spider 61. A spider 63 also encircles the shaft 27 and connects the sleeve 60 with the shaft providing support for the shaft as the spider 63 is equipped with a flange 64 secured to the top 65 of the separating chamber of the casing 10.

10 A series of links 66 are pivotally secured to the top 65 of the casing 10 and are pivotally secured at their lower end to the cone 57. Thus the cone 57 is supported for a limited rotation and is also axially movable along the shaft 27. 15 When grain flows through the screen 37 and builds up between the ring 35 and the cone 57 sufficient friction is created to cause some rotation of the cone 57, swinging on its supporting links 66 and thus the opening 67 or space between 20 the lower extremity of the cone 57 and the ring 35 may be increased when necessary.

A series of angularly spaced supports 69 extends upwardly from the casing 10 to support an aspirating casing 70. This aspirating casing is a hollow cylindrical casing having a cylindrical outer wall 71, a bottom partition 72, and a top partition 73. An opening is provided in the bottom partition 72 to coincide with the opening provided by the sleeve 60, the sleeve 60 extending through this opening. An aspirating deflector 74 is mounted upon the shaft 27 and is rotatable therewith, this aspirating deflector changing the direction or flow of air through the chamber. Paddles 75 are rotatable with the deflector to guide any material caught in this aspirating chamber toward a suitable outlet not illustrated.

The top 73 of the aspirating chamber is connected by means of the pipe elbow 76 to a blower or fan 77 located in the fan casing 78. The blower or fan 77 is mounted upon a shaft 80 upon which is also mounted a pulley 81. This pulley 81 is in alignment with a pulley 82 on the shaft 24 and a belt connects the pulleys 81 and 82 to drive the fan 77 when the machine is in operation.

40 In the operation of the separator, the grain is placed in the inlet hopper 44 and the flow of grain from this hopper into the separator is regulated by means of the gate 45. The grain 45 falls into the space between the screen 37 and the wall of the casing 10. As the grain is dropped, the cylindrical screen 37 rotates within the ring-shaped baffle 40.

During the rotation of the screen 37 the small 55 seeds and small grain such as wheat for example, if this wheat is the grain desired, passes through the opening in the screen 37. The larger grains such as oats cannot pass through the screen and are carried along by friction toward a suitable outlet. The bristles 52 of the brushes 51 contact the outer surface of the screen and permit long grain such as oats which lie flat against the screen in indentations therein to pass the brushes. Most of the material, however, too 60 large to pass through the screen is urged up along the inclined brushes and is thus carried away from the smaller grains and smaller material. The sticks, stones, straw and other material too long or too big to pass through the screen perforations are gradually drawn up each of the 65 inclined brushes dropping to a point near the base of the next adjacent brush. The friction of the grain as the cylindrical screen rotates, causes this movement of the grain and no paddles, agitators, or the like are usually necessary.

During this process the larger particles of the impurities, such as the sticks, stones and larger particles of straw, are dropped from one of the brushes 51 into a chute or discharge trough 83 which is positioned below the end of one of the brushes 51. Another chute 84 projects into the casing 10 beneath the end of the next adjacent brush 51 to catch foreign material which rides up this inclined brush. The material which is discharged through the discharge chute 84 is ordinarily smaller than that passing out through the discharge 83 as only the smaller material works through the bristles 52 of the inclined brushes. A discharge passage 85 is provided for the oat and remaining material which passes by the inclined brushes 51 and which is too large to pass through the screen 37. A partition wall 86 provided with a sealing gasket 87 prevents the flow of any of this material too large to pass through the screen 37 beyond the chute 85.

The invention has found that with his system of brushes he can separate the larger and smaller particles of foreign material ordinarily found in grain. The large impurities are discharged through the chute 83, the slightly smaller impurities are discharged through the chute 84, and only the material passing through the chute 85 is almost entirely composed of oats. With this system large materials are separated from the smaller material, thus preventing the bunching of all of the impurities together. When impurities become bunched together, grain is extremely apt to be intermingled with the impurities as these impurities prevent the grain from contacting the separating screen 37. The wire brushes, however, are inclined longitudinally and also longitudinally of the bristles so that the grain passing up the wire brushes rests upon the bristles of the brushes and has a tendency to contact the screen or to work through the bristles. In this way the grain is more effectively and efficiently cleaned and the inventor has found that all of the grain has an opportunity of contacting the screen for separation.

The manner in which the grain passing through the screen 37 drops between the cone 57 and the link 35 to be spread into a cylindrical sheet for aspirating purposes, and the manner in which the seeds are separated by the screen 32 from the wheat has been fully described in the co-pending application previously referred to. The inventor has found that it is usually beneficial to use for the screen 37 a screen having a series of pockets or indentations therein which indentations are perforated in the manner illustrated in this previous application.

With this construction the oats and smaller impurities are carried by the pockets past the

bristles 52 of the brushes 51 and are virtually entirely separated from other impurities. The chute 83 catches all of the larger impurities while smaller material such as corn which has a tendency to work through the bristles is usually expelled through the chute 84. It will be noted that the brush 51 adjacent the chute 84 is shorter than the remaining brushes and the shortness of this brush does not give the material such as corn the same opportunity to work through the bristles as the longer brushes 51 in the series.

In accordance with the patent statutes I have described the principles of construction and operation of this separator and while I have endeavored to set forth the best embodiments thereof, I desire to have it understood that these are only illustrative of a means of carrying out this invention and that obvious changes may be made within the scope of the following claims without departing from the spirit of this invention.

What is claimed is:

1. A grain separator including a perforated rotary cylinder having a substantially vertical axis, a casing surrounding said cylinder, an adjustable hopper for feeding grain between said casing and said cylinder, a supporting shelf extending between said casing and said cylinder, brush means yieldingly contacting said cylinder and flexibly contacting said shelf and being inclined in the direction of rotation of said cylinder, said cylinder perforations permitting smaller grains to pass through the cylinder, an outlet chute for the small grains, said inclined brush means elevating larger impurities through movement of said cylinder and out through a separate outlet chute and said cylinder rotation carrying larger grains incapable of passing through said cylinder past said inclined means and out through a separate outlet chute.

2. A grain separator comprising a perforated rotary vertical cylinder, a casing surrounding said cylinder, means for feeding grain between said casing and said cylinder, inclined brush means yieldingly contacting the outer surface of said cylinder and being inclined in the direction of rotation of said cylinder, said cylinder perforations permitting smaller grains to pass through the cylinder, an outlet chute for the small grains, said brush means adapted to guide material incapable of passing through said screen upwardly out through an outlet chute upon the rotation of said cylinder, and said cylinder rotation carrying larger grains incapable of passing through said cylinder past said inclined means out through a separate outlet chute.
